(57) CLAIM

The ornamental design for a planter/feeder, as shown and described.

DESCRIPTION

FIG. 1 is a top perspective view of a planter/feeder, showing our new design.

FIG. 2 is a top plan view thereof.

FIG. 3 is a front elevation view thereof.

FIG. 4 is a left side elevation view thereof; and,
FIG. 5 is a right side elevation view thereof.

The broken lines depict environmental subject matter only and form no part of the claimed design.
